UNITED STATES PATENT OFFICE.

FRED T. WITHEE, OF SPRINGFIELD, MASSACHUSETTS, AND ROBERT WHITE, OF CLEVELAND, OHIO.

TAKE-UP FOR LOOMS.

No. 903,146.

Specification of Letters Patent.

Patented Nov. 3, 1908.

Original application filed September 28, 1906, Serial No. 336,547. Divided and this application filed August 7, 1907. Serial No. 387,512.

To all whom it may concern:

Be it known that we, FRED T. WITHEE, a resident of Springfield, in the county of Hampden and State of Massachusetts, and ROBERT WHITE, a resident of Cleveland, in the county of Cuyahoga and State of Ohio, both citizens of the United States of America, have invented new and useful Improvements in Take-Ups for Looms, of which the following is a specification, the same being a divisional part of an application for United States Letters Patent filed by us September 28, 1906, and serially numbered 336,547.

Our invention relates to improvements in power looms designed especially for weaving wire-cloth, and more particularly to mechanism for taking up or rolling up the cloth as it is woven, and consists essentially of alternately actuated weighted arms with subsidiary and auxiliary parts, all as hereinafter set forth.

The object of our invention is to provide positive and efficient yet simple mechanism which acts on the cloth-roll to produce the constant and necessary tension on the warp and to roll up the cloth as fast as it is woven.

A further object is to provide such mechanism which can be operated either automatically or pedally.

We attain these objects by the mechanism illustrated in the accompanying drawings, in which—

Figure 1 is an end elevation of a loom embodying our invention, certain parts of the loom which are not necessary to a clear understanding of said invention being left out, and, Fig. 2, a plan view of one of the take-up arms and associated parts.

Similar figures refer to similar parts throughout the several views.

A suitable frame is represented at 5 for a warp-beam 6, a vertical shaft 7, a drive-shaft 8, a shaft 9 in front of said drive-shaft and driven from the latter through the medium of meshing gears 10 and 11, a breast-roll 12, a cloth-roll 13, a batten 14, and the warp and cloth-take-up mechanism presently to be described, the warp-beam and the cloth-roll being indicated by dotted lines.

The warp-beam shaft 15 is journaled at each end in a bearing-block 16, a bracket 17 being provided at each end of the frame 5 for such bearing-block, and bolts 18—18 in each bracket affording means for the adjustment

of the bearing-block therein. At 19 is a worm-gear on the warp-beam which meshes with a worm 20 on the shaft 7.

21 represents a peg-wheel on the shaft 7 which peg-wheel is governed by suitable escapement let-off mechanism not herein shown. The gear 10 is tight on the shaft 8 and the gear 11 tight on the shaft 9. The drive-shaft 8 is mounted in the lower part of the frame 5, in advance of and parallel with the warp-beam, and has power transmitted thereto in any suitable manner and from any suitable source. The breast-roll 12 and the cloth-roll 13 respectively guide and receive the cloth as it is woven, and their respective shafts 22 and 23 are mounted in the frame. The batten 14 is mounted to swing on the frame, a bolt 24 affording means for vertical adjustment, and a notched rest 25 and its supporting bolts 26 affording means for horizontal adjustment, these members being the same at both ends of the loom. The slay is represented at 27 and the reed at 28.

The slay 27 is actuated by a cam 29 on the drive-shaft 8 and a spring 30, through the medium of pivotally-connected arms 31 and 32 generally arranged in pairs, the former being mounted on a suitably supported rock-shaft 33 and the latter being pivoted as at 34 to the slay. The cam 29 acts on a roller (not shown) carried between the arms 31. The spring 30 has one end attached to one of the arms 31 and the other connected by turn-buckle members with a hook 35 in the floor. Two springs 30 and their connections are usually employed.

The warp-wires 36 pass from the warp-beam 6, through the heddles indicated by the dotted lines 37 and through the reed 28, over the breast-roll 12 to the cloth-roll 13. Little more of the shedding mechanism appears except the two treadles 38 which operate the heddles and are themselves operated by cams on the shaft 9, a portion of one of such cams being seen at 39.

While the parts above pointed out may be generally old and well-known, an understanding thereof is desirable not to say necessary in order to fully comprehend the new features, with some of which latter such parts enter into quite close combination as will be seen from the following description of said features.

As already intimated, the take-up not only winds up the cloth as woven on the roll 13, but keeps a tension on the warp wires 36. This take-up mechanism comprises a ratchet-wheel 40 on each end of the cloth-roll shaft 23, a lever or arm 41 mounted on said shaft in operative relation with each ratchet-wheel and carrying a weight 42 at the end opposite the shaft, a pawl 43 pivoted to each arm at 10 44 and arranged to engage the teeth on the associated ratchet-wheel in front, and a cam 45 on the shaft 9 below each arm. The front terminals of the arms 41 are preferably forked, as shown in Fig. 2, and each of said 15 arms is provided with a roller 46 adapted to bear on the cam 45 below.

The arms 41 are oscillated alternately through the medium of the cams 45 and contacting rollers 46, one arm at each revolution of the drive-shaft 8 since the gears 10 and 11, on the shafts 8 and 9, respectively, are as two to one, that is, the gear 10 makes two revolutions to one of the gear 11, and as such arm oscillates its pawl 43 rotates the associated ratchet-wheel 40 provided the movement of the arm is sufficient to enable said pawl to advance a tooth. In this way the shaft 23 is rotated to wind up the cloth on the roll 13 and to draw the warp from the beam. Except at the instant of being raised by the cams 45 the weight of the loaded arms 41 comes on the roll 13 and the warp-wires 36 because of the engagement of the ratchet-wheels 40 by the pawls 43, therefore the desired tension is always maintained on said wires.

By adding to the take-up mechanism described above the foot-power device shown in Fig. 1, the take-up can be operated ped-
ally. This device consists of a treadle 47 having its rear end pivoted at 48 to the ad-
jacent end of the frame 5, a pawl 49 pivoted
at 50 to said treadle and pressed by a spring
51 into engagement at the back of and with
45 the ratchet-wheel 40 with which said device
is associated, said spring being also attached
to the treadle, and a spring 52 between the
floor and the bottom of the treadle. A pin
53 extending outward from the end of the
50 frame above the free terminal of the treadle
47 limits the upward movement of said
treadle.

A loom is usually provided with only one

foot-power device, although there might be two for the sake of convenience, one at each end of said loom, but in the event that there were two both would not be used at the same time. The device is to be employed when for any reason the cams 45 are not in operation, and it works in conjunction with the weighted arms 41 and the pawls 43, or with one of such arms and its pawl when the other arm happens to rest on its cam, the arm or arms furnishing the tension for the cloth-roll or for the warp and the treadle 47 with the pawl 49 causing said cloth-roll to be rotated each time said treadle is depressed against the resiliency of the spring 52. As the treadle is lifted by the spring 52, after being depressed by the foot of the operator, the pawl or pawls of the active arm or arms reengage the teeth on one or both ratchet-wheels 40 and thus not only prevent the cloth-roll from turning backward but place the same under tension. 75

The weights 42 are arranged to slide on the arms 41 so that they can be easily adjusted thereon to vary the amount of tension exerted by said arms on the ratchet-wheels 40, and a bolt 54 is provided for each weight with which to tightly secure the same to the arm upon which it is mounted, after adjustment. 11

What we claim as our invention, and desire to secure by Letters Patent, is—

The combination, in a loom, with the cloth-roll shaft and a ratchet-wheel thereon, and a weighted arm mounted on said shaft and provided with a pawl arranged to engage said ratchet-wheel, of a pivotally-mounted upwardly spring-pressed treadle provided with a spring-pressed pawl also arranged to engage the ratchet-wheel, whereby the cloth-roll shaft may be intermittently rotated by means of the foot of the operator, the pawl on said weighted arm serving as a detent at such time. 90 95
